Primary Examiner — Robert M Spear*Assistant Examiner* — Marissa J Cash(74) *Attorney, Agent, or Firm* — Muncey, Geissler, Olds & Lowe, P.C.(57) **CLAIM**

The ornamental design for a bipolar cutting instrument, as shown and described.

DESCRIPTION

FIGS. 1-7 illustrate an enlarged view of the cutting tip of the bipolar cutting instrument.

The dashed lines illustrate environment that does not form a part of the present invention, and no claim is made to the material illustrated with dashed lines.

1 Claim, 4 Drawing Sheets(56)
